UNITED STATES PATENT OFFICE.

DAVID FISHER, OF PADEN CITY, WEST VIRGINIA, ASSIGNOR TO PADEN CITY GLASS MANUFACTURING COMPANY, OF PADEN CITY, WEST VIRGINIA, A CORPORATION OF WEST VIRGINIA.

DESIGN FOR A PITCHER.

Application filed September 22, 1925. Serial No. 14,849. Term of patent 7 years.

To all whom it may concern:

Be it known that I, DAVID FISHER, a citizen of the United States, residing at Paden City, West Virginia, have invented a new, original, and ornamental Design for Pitcher, of which the following is a specification, reference being had to the accompanying drawings, forming a part thereof.

In the drawings, Fig. 1 is a side elevation of a pitcher, showing my new design; and Fig. 2 a similar view looking towards the handle side thereof.

I claim:

The ornamental design for a pitcher as shown.

DAVID FISHER.
